UNITED STATES PATENT OFFICE

2,057,146

SUBMARINE EYE

Charles W. Heath, Sioux City, Iowa

Application July 28, 1932, Serial No. 625,305

7 Claims. (Cl. 61—69)

My invention relates to an apparatus intended for locating or transferring images from the bottom of the sea to the surface.

An object of my invention is to provide means

5 for lowering a television apparatus to a short range from the sea floor and transmitting the images thus formed by television means to a vessel on the surface.

A further object of my invention is to provide 10 positive sealing means for sealing the television apparatus which is lowered.

A further object of my invention is to provide 15 powerful lighting means to illuminate the sea floor so that the images can be clearly distinguished.

A further object of my invention is to provide 20 means for tilting the television eye which is lowered, so that the viewpoint can be transferred to any desired angle.

A further object of my invention is to provide 25 means for effecting a clear view and defining the image to the greatest possible extent.

A further object of my invention is to provide 30 means for proper synchronization of the television apparatus as well as means for adjusting the synchronization perfectly after it is out of step.

A further object of my invention is to provide 35 suitable means in the vessel which receives the images to clearly define the image in the best possible manner.

A further object of my invention is to provide 40 automatic control means for regulating the television eye to any desired position as well as controlling the eye for any contingency.

A further object of my invention is to provide 45 all of the above mentioned objects in a construction which is as simple as possible for the purpose intended so that there will be a minimum of apparatus to get out of order.

With these and other objects in view, my invention consists in the construction, arrangement and combination of the various parts of my device, whereby the objects contemplated are 50 attained, as hereinafter more fully set forth, pointed out in my claims, and illustrated in the accompanying drawings, in which:

Figure 1 is an elevation showing the method 55 of supporting the submarine eye from a vessel.

Figure 2 is a modified form showing the structure attached to the eye for obtaining a superior angular positioning effect.

Figure 3 is a sectional view of the submarine 60 eye itself.

Figure 4 is a bottom view of the eye,

Figure 5 is a plan or top view.

Figure 6 is a view of the wiring diagram for the apparatus together with details of the receiving table.

Figure 7 is an enlarged detail view of the 5 clamping method for clamping the bell of the eye to the window structure, and guard framework.

Figure 8 is an enlarged detail view showing 10 the method of incorporating the lenses in the television scanning disks.

Figure 9 is a plan view of the pick-up scanning disk.

Figure 10 is an elevation of the control and 15 receiving table.

Figure 11 is a plate view of the table, and

Figure 12 is a modified view showing a motion 20 picture camera attached to the table.

In exploring the sea bottom, the problems 25 encountered are numerous. For instance in locating sunken treasure no satisfactory means have been devised for determining what is at the bottom of the sea at particular locations.

It is generally necessary for divers in suitable 30 diving suits to be lowered to the sea floor and make observations. This entails a great deal of labor and expense even before the objects are definitely located. At the best the present variety of tubes, diving bells and the like necessitate the human element being positioned near 35 the scene of observation. In other words the person or persons involved must be lowered to the sea floor. Since ordinary diving suits and the like and the human element are limited to certain pressure restrictions, this is a very inconvenient method of locating or visualizing objects on the sea floor.

It is my intention in my present invention to 40 show that I have devised a method of directly visualizing objects on the sea floor just as definitely and as accurately as though the observer were on the sea floor himself. Furthermore I will show that I have devised such an apparatus which can be lowered to a very great depth.

Furthermore I will show that I have devised 45 such an apparatus which can be readily adjusted by suitable controls so that the eye itself can be positioned at an angle to its normal plane.

I have used the reference character 10 to designate the sailing vessel which is used with the submarine eye. This vessel carries the extended arms 11 which are placed at the bow stern port and starboard side respectively.

All of these arms will be of approximately the 50 same length with possibly the arms on the port 55

and starboard sides being of greater length for reasons to be stated.

The arms 11 include the pulleys 12 at their extremities, over which the cables 13 pass.

5 It will be seen from this that there are four cables passing downwardly from the extended ends of these arms.

The inner ends of the cables 12 are attached to suitable winches on the deck which need not 10 be detailed here.

The cables 13 pass downwardly and are attached to the submarine eye itself through the openings 14, (see Figure 3), of which there are 15 four spaced equally about the upper periphery 16 of the bell 15.

The openings 14 are included in the integral extensions 16 which are cast solidly together with the bell 15.

An upper eye opening 17 is provided for emergency means for drawing the eye to the surface 20 or to the deck of the boat if desired. For instance after the eye is drawn nearly to the surface of the water, the hook 18 can be lowered from a derrick or the like and engage in the 25 opening 17 and the eye drawn upwardly to the deck since it would not be possible to conveniently perform the same operation with the four cables 13.

The bell 15 is made of strong cast metal to 30 withstand the extreme pressures involved at great sea depths.

I also provide the fin 19 to prevent oscillation of the eye about its vertical axis and which fin will tend to keep the eye in a substantially stationary position.

The fin 19 includes the ribs 20 and the portion 21, which is adapted to be bolted by the same bolting means which bolts the rest of the apparatus together and which will be explained 40 more fully.

It will now be seen that the submarine eye is suspended from four cables 13, which are widely separated at their upper ends. This type of structure is important since it is necessary in an 45 apparatus of this type to prevent the eye from swaying about its axis and to keep it as stationary as possible when lowered. For instance if a single cable were used, the various currents encountered in the sea depths would tend to 50 oscillate the eye about the axis of the cable and unsatisfactory results would be obtained. However in the present construction the separating of the cables spaces the supporting means so that the angular effect is correspondingly increased 55 and there can then be no undue twisting of the cables.

To further emphasize this effect for greater depths, I provide the modifications shown in Figure 2 in which the frame 22 is bolted to the 60 same bolted means which bolts the submarine eye apparatus together, and the bracing arms 23 are provided to brace this member.

The cables 13 are then attached to the outer ends 24 of these structures. In this way the 65 twisting effect is reduced.

When the submarine eye is lowered, the winches controlling the cables 13 are reversed, thus allowing the eye to drop uniformly towards the bottom of the sea.

70 The controls for controlling these cables will be discussed later.

The eye will travel in horizontal position downwardly until the television apparatus, which will be explained, starts to pick up the views on the 75 sea floor.

The positioning of the eye as far as height above the sea floor is concerned can thus be determined visually.

If it is desired to sight the object at an angle, any one, two or three of the cables 13 can be lowered or raised as desired, thus effecting an angular positioning of the submarine eye to locate objects from any angle.

For instance the eye can be placed at a suitable angle so that its flat surface travels in the direction of the vessel so that as the vessel cruises, the images are constantly picked up.

I will now proceed to elaborate more fully on the television and other apparatus.

Light impulses picked up by the television 15 apparatus are carried electrically to the surface vessel by means of the multi-conductor cable 25, which passes through the eye at the point 26 and which can be a stuffed type of connection as shown, or in more extreme cases under conditions of extreme pressure where the cable would be lead covered or armour covered, the same cable can be wiped to a suitable brass sleeve and bolted to the bell.

In the present apparatus this cable would be a 25 four conductor cable.

Two of the wires, in cable 25 would carry a 110 volt alternating current down to supply the posts 27 to the head amplifier 28.

The same supply would then pass through the 30 wires 29 through the conduits 30 and thence downwardly through the stuffed type of connection or the other as explained 31 into the submarine lamps 32.

The submarine lamps 32 are of the usual commercial type, which are built to withstand pressures of the type usually met in submarine work and are attached to suitable brackets 33.

The stuffed connection at 31 is solidly packed and is a construction well known in the art and can be made to withstand extreme pressures as 40 desired.

There are five lamps 32 as shown in Figure 4 which are electrically connected in multiple from the same circuit by means of the cables 32a.

Part of the 110 volt supply also passes to the 45 motor 34 where it is attached to the binding posts 35.

These connections can be made in any way just so they are suitably connected in multiple.

The motor 34 drives the scanning disk 36 by means of the directly connected shaft 37a.

The scanning disk is made in the usual way well known in the television art and includes the spiralled arrangement as shown in Figure 9, 55 and in this case a pair of spirals are used such as 37 and 38. Each spiral includes the small openings 39 and there are approximately sixty in each group.

To direct or project the optically dissected portion of the view, which normally is in front of the pick-up television apparatus upon the photo electric cell, I use a plano-convex lens 40. (See Figure 8.)

This is a small lens which is placed in each opening 39 in the scanning disk.

The scanning disk can be made of suitable metal such as aluminum or the like, and each opening 39 includes the shoulder 41, upon which the lens 40 rests, and the metal of the disk is very slightly peened over as at 42 to retain the lens 70 solidly.

The lenses 40 in the scanning disc 36 pass in a plane perpendicular to the path of the light and by their optical effect cut the picture or view

projected through the opening 46 into very thin slices or ribbons of light, the varying intensities of which light are registered on the photoelectric cell 43 where the light impulses are changed to electrical impulses.

Beneath the scanning disk 36 is positioned the light shield 45, which is adapted to keep stray light from striking the photoelectric cell prematurely and which includes the openings 46 for allowing the view to pass therethrough.

The scanning disk is of the usual type, and it performs the function of breaking up the picture into a series of vertical lines as indicated in the dotted figures in Figure 9 at 47.

15 In this case, due to the sixty openings per spiral, the view will be made up of sixty lines per picture paralleling each other.

48 indicates the usual photographic lenses supported by the adjusting brackets 49.

20 To the right hand lens is supported the additional lens 50, which is a cylindrical type lens. This lens gives the right hand light beam a mirror-like reversal from top to bottom, but not from side to side, so that both photoelectric cells 25 43 and 45 will scan the scene together in a uniform manner.

The photographic lenses 48 perform the function of concentrating the light rays to the photoelectric cell 45, and the variation of the light 30 intensity imparted to the photoelectric cell through the scanning disk lenses varies the current in the photoelectric cell which is amplified by the amplifier 28 and passes on to the receiving set on board the surface boat 10 through the wires 51.

35 It will be seen that these wires are the other pair of the four wire conductors 25.

The connection from the photoelectric cells is made by means of the wires 52 on each side of the circuit.

40 It will be noted from a study of my Figure 3 and Figure 9 that the left hand photoelectric cell 43 is positioned to scan through the outer spiral of the scanning disk, and the right hand cell 44 is positioned to scan through the inside spiral. In 45 this way and due to the fact that the spirals are arranged as shown, the image will be picked up simultaneously and by means of the double cell is more pronounced, and a clearer view will be obtained. These principles are well known in the 50 art. Of course, if desired, it will be understood that the single spiral and cell arrangement can be used.

Clamped to the bell 15 is the end plate 53, which is clamped against the flange 54 and the gasket 55 retained therebetween. This gasket is made of rubber or any suitable gasket necessary to withstand great pressures and the like.

Attached to the underside of the plate 53 are the guards 56 of which there are four as shown 60 in the top and bottom views of Figures 5 and 4 respectively.

These guards are made of heavy sheet metal and about their ends is attached the angle iron 57 which is riveted at 58.

65 This angle will thus form a complete circle and will serve to reinforce the members 56.

As a further method of strengthening the members 56, I provide the additional circular strips 59, which are also riveted to the members 56. This 70 structure provides an efficient guard for the lamps so that they will not strike objects on the sea floor, or during the transit of the eye to the floor, and in case the eye strikes the sea floor the guard will also prevent injury to the lamps.

75 The guard is made of this open structure so

there will be no tendency for any such effects as swaying of the eye as it is lowered, or due to the passage of water currents against the guards. For instance if the guards 56 were made saucer-shaped or as a complete continuous shell, these effects 5 would be pronounced, and I have provided the guards in a more open structure to offset these effects.

The plate 53 includes the openings 60 for the light to pass through.

To seal the plates and at the same time provide light transmitting means, I provide the heavy and comparatively thick quartz windows 61. These windows set within the recesses 62 and are compressed against the gaskets 63.

10 A pair of annular rings 64 serve to maintain the pressure against the gasketed surfaces, and the gaskets 65 are placed beneath the flanges 66 of these rings.

15 These rings are suitably bolted as shown in Figure 4 by means of the bolts 67.

The guards 56, the plate 53 and the bell 15 are bolted together through the flange 54 as shown in Figure 7 where a long bolt 58 is used passing through a threaded portion in the plate 53 and 25 through a clearance hole 68 in the flange 54.

The end of the bolt such as 69 is made sufficiently long in case the projecting arms 22 (see Figure 2) or the fin 19 is to be placed on this flange.

Lock washers 70 are also provided. The structure is made in this way so that the lower plate 53 can be separated from the bell for adjustments inside of the bell and so that these various units can be separated as desired.

20 The photoelectric cells are supported by means of the brackets 71 to the inside of the bell and the plate 45 by means of the various brackets 72.

It will be noted that the end plate 53 includes the integral ribs 73 which are made of very rugged construction and comprise uniform sections 40 through vertical planes at right angles to each other so that this ribbing will be in a square form approximately in the center with the motor 34 placed therein.

25 This ribbing of course is necessary to insure 45 great strength to the plate.

I will now pass from the transmitting apparatus to the receiving arrangement within the surface vessel.

30 The fluctuating current impulses passing from 50 the photoelectric cells and through the amplifier 28 by means of the binding posts 52 and 54 which connect the circuits to these cells will be amplified and pass upwardly through the cables at the binding posts 51.

35 The impulses will pass from the photoelectric cells 43 and 44, through the head amplifier 28, which contains amplification, modulation, and oscillator etc., and suitable filter units functioning to properly amplify the vision current to a suitable carrier current, prior to transmission to the main amplifier 112 of the receiving set on board the vessel via wires 116 (see Fig. 5). The main amplifier 112 contains units for further filtration, 60 modulation and amplification suitable for presentation of the vision current through wire 118 to the tube 74 and grid 75 (the receiving light sources) for integration of the vision picked up by the eye below. The double shield 78a is provided to prevent rays of light from straying.

65 The mechanical part of this apparatus will be now explained and the circuits explained later.

70 The "Crater" arc tube is fixed to the revolving table 77, which revolves independently of the motor 78.

The table 77 is suitably journaled on the motor housing at 78 where this portion receives the bearing 80.

The motor shaft 81 passes through the portion 5 79 and is pinned at 82 to the further scanning disk 83.

The fluctuating light impulses from the tube 74 pass through the scanning disk in the usual manner well known in the art up to the mirror 83a, 10 which is pivoted at 84 to the bracket 85.

The projection lens 86 is interposed between the scanning disk and the mirror 83a to spread the image to a greater extent and is pivoted to the bracket 85 at 87.

15 The lower end of the bracket 85 is also rigidly secured to the rotating table 77.

At the other end of the table is attached the bracket 88 at 89.

20 The hinges 90 and 91 are provided with an upper part of the bracket 82 including the slotted opening 93 for adjusting purposes.

The upper extended bracket 94 includes the pivot 95, to which is attached the further mirror 96 which receives the image from the mirror 83a.

25 The mirrors 96 and 83a are so arranged that the natural optical laws are correctly followed in order to transpose the image properly and upwardly to the ground glass visioning screen 97 where the identical image which is picked up at the bottom 30 of the sea, will be transposed on this screen as shown in Figure 11.

The table 98 is provided to carry the various switch rheostats and other control devices.

35 The rotatable table 77 is rotated by means of the belt 99 which passes through the groove 100, which belt also passes around the further wheel 101. (See Figure 10.)

The wheel 101 is directly driven by the shaft 102, which is secured to the knob 103.

40 The belt 99 is of a suitable type so that the tension in the belt will be maintained uniformly.

The purpose of this arrangement is as follows:

In case the receiving scanning disk 83 or the transmitting scanning disk 86 are out of phase 45 due to coasting of one of the disks or any one of the other influences during adjustment, by simply turning the knob 103 the table 77 can be rotated slowly as desired until the image is no longer jumbled and is picked up perfectly. This will inform the observer that the disks are again in 50 phase.

The effect of this apparatus is merely to turn the tube 74 so that the identical analogous openings in the scanning disk are uniform so that the 55 pictures are transmitted perfectly and of course the associated mirrors are carried in a positive manner so that the effect produced is entirely uniform.

It will be noted that the table 77 is thus rotated in a free manner not associated with the shaft 81 of the motor 78 so that these two mechanisms are entirely separate.

For controlling the cables 103 for tilting or lowering the submarine eye, I provide the double 65 throw switches 104, 105, 106, 107 and 108, where 104 controls the port side arm, 105 the stern arm, 107 the bow arm, 108 the starboard arm and 106 is a master switch controlling all cables 103 simultaneously. In other words by throwing these 70 switches one way or the other an upward or downward movement of the cables 103 can be controlled individually, or by moving all of the cables at once.

These switches are connected to motors, 75 winches and the like for reeling or unreeling the

cable, which need not be shown here, and the wiring arrangements need not be shown since they are well known to anyone in the art.

The rheostat 109 is connected in to the 110 volt line circuit so that the current may be fed properly and is really the rheostat which controls the main circuit. 5

The rheostat 110 regulates the current from the line to the switches aforementioned, namely the cable controlling switches. 10

The rheostat 111 is used to compensate for the internal resistance of the different lengths of cable which will be used and for other reasons. The primary reason however is to balance the 15 electrical resistances between the upper receiving set and the lower transmitting set. Such variations may be involved in a case where it may be very warm on the surface of the water but cold in the sea depths, thereby causing a difference in synchronization in the operation of the two scanning disc motors. This resistance will compensate for this condition as well as to other conditions. 20

In this way the scanning disks will be perfectly synchronized, due to the present method of the circuit connections. 25

The character 112 designates the main amplifier (see Figure 10), where the letter H represents a rheostat to control the heater element of the arc tube and where F is the rheostat controlling the filaments of the amplifier tubes, and B the 30 rheostat controlling the plate voltage.

The wiring diagram in Figure 10 is not shown complete to avoid confusion since a more satisfactory diagram is shown in Figure 6.

The wiring diagram will now be briefly explained. (See Figure 6.) The head amplifier is represented by the character 28 and receives the 35 110 volt circuit at 27 from line 113 in Figure 6 which lines are controlled by suitable rheostats as explained.

The 110 volt circuit passes through the lines 114 to the motor 34 and thence to the powerful lamps 32. These lines are similar to the lines 29 in Figure 3 which pass through the conduits 38.

The photoelectric cells 43 and 44 are connected 45 to the lines 115 at 52 as shown in Figure 3, and to the head amplifier 28.

The thumb screw 120 is arranged to adjust the arc tube base in an outward movement to give the radial adjustment desired. 50

The head amplifier 28 is the usual type such as a two tube amplifier (resistance coupled) and of course the main amplifier 112 is of the construction commonly used.

The character 121 represents the compass and 55 122 a map or such necessary chart.

As a modification of the device it would become somewhat important to take motion pictures of objects such as marine life and the like at the bottom of the sea. To accomplish this means I 60 have shown generally the motion picture camera 123, which is rigidly secured to the brackets 124, which are secured to the table at the dotted portions 125 so that the camera will directly overhang the screen 87 and so that pictures can be 65 taken.

This feature would serve the valuable purpose of allowing photographing of the sea bottom as it actually is and as it is in motion so that these pictures can be obtained without the necessity of 70 lowering some cumbersome apparatus which is now used.

It will now be seen that I have provided a submarine eye which can be readily lowered to the bottom of the sea from the surface, which eye 75

contains a television apparatus which directs the image upwardly through light and electrical effects to a surface boat.

It will also be seen that I have provided such an eye which is positively sealed to withstand great pressures, which also includes apparatus to illuminate the sea floor properly.

It will be seen that I have provided means for tilting the submarine eye to a suitable angle for properly scanning the sea floor. It will also be seen that I have provided such an apparatus of the type involving factors of simplicity as against the objects accomplished.

Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

1. An apparatus of the character described comprising a surface vessel including television receiving means, a submarine eye including means for withstanding deep sea pressures suspended in submerged relation to the surface vessel, including television transmitting means connected to the television receiving means of the surface vessel, and non-twisting means for supporting the eye, including a plurality of wide spread and downwardly converging cables attached to the surface vessel and the eye, and means for causing angular positioning of the eye to a non-parallel relationship with respect to a sea floor.

2. An apparatus of the character described comprising a surface vessel including television receiving means, a submarine eye including means for withstanding deep sea pressures suspended in submerged relation from the surface vessel, including television transmitting means connected to the television receiving means, said submarine eye including a bell, a horizontal end plate secured to the bell including windows positioned to transmit images from a sea floor to the television means, and means for illuminating the sea floor, including a plurality of submarine lamps attached beneath the eye, and means for guarding the lamps.

3. An apparatus of the character described comprising a surface vessel including television receiving means, a submarine eye including means for withstanding deep sea pressures suspended in submerged relation from the surface vessel, including television transmitting means connected to the television receiving means, said submarine eye including a bell, an end plate secured to the bell including windows positioned to transmit images from a sea floor to the television means, said television means including a scanning disc, a motor driving the scanning disc, a photographic lens positioned above the scanning disc, a photoelectric cell positioned above the photographic lens, and electrical means for transmitting electrical fluctuations upwardly to the receiving television means.

4. An apparatus of the character described comprising a surface vessel, including television receiving means, a submarine eye including means for withstanding deep sea pressures suspended in submerged relation from the surface vessel, in-

cluding television transmitting means connected to the television receiving means and illuminating means attached beneath the submarine eye, including a plurality of lamps adapted to throw light beams downwardly at right angles to the general horizontal plane of the submarine eye, non-twisting means adapted to prevent oscillation of the submarine eye, including a plurality of wide spread and downwardly converging cables attached to the eye from the surface vessel.

5. An apparatus of the character described comprising a surface vessel, including television receiving means, a submarine eye including means for withstanding deep sea pressures suspended in submerged relation from the surface vessel, including television transmitting means connected to the television receiving means and illuminating means attached beneath the submarine eye, including a plurality of lamps adapted to throw light beams downwardly at right angles to the general horizontal plane of the submarine eye, non-twisting means adapted to prevent oscillation of the submarine eye, including a plurality of wide spread and downwardly converging cables attached to the eye from the surface vessel, and means for decreasing the convergency of the cables, including a four-point wide spread structure attached to the eye.

6. An apparatus of the character described comprising a surface vessel, including television means, a submarine eye, including means to withstand deep sea pressures suspended in submerged relation from the surface vessel, including television transmitting means connected to the television receiving means, non-twisting means for supporting the eye, including a plurality of wide spread and downwardly converging cables attached to the surface vessel and the eye, said receiving means including means for synchronizing the transmitting scanning disc with the receiving scanning disc, including a motor adapted to rotate the scanning disc, a rotatable table freely journaled about the bearing of the motor, means for manually rotating the table to desired phase relationship, reflecting mirrors attached to the rotating table, and a translucent screen positioned about the reflected mirrors and adapted to receive the reflected images thereon.

7. An apparatus of the character described comprising a surface vessel, including television means, a submarine eye, including means to withstand deep sea pressures suspended in submerged relation from the surface vessel, including television transmitting means connected to the television receiving means, non-twisting means for supporting the eye, including a plurality of wide spread and downwardly converging cables attached to the surface vessel and the eye, said receiving means including means for synchronizing the transmitting scanning disc with the receiving scanning disc, including a motor adapted to rotate the scanning disc, a rotatable table freely journaled about the bearing of the motor, means for manually rotating the table to desired phase relationship, reflecting mirrors attached to the rotating table, and a translucent screen positioned above the reflecting mirrors and adapted to receive the reflected images thereon, and means for taking motion pictures positioned above the translucent screen.

CHARLES W. HEATH.

CERTIFICATE OF CORRECTION.

Patent No. 2,057,146.

October 13, 1936.

CHARLES W. HEATH.

It is hereby certified that error appears in the printed specification of the above numbered patent requiring correction as follows: Page 5, first column, line 19, after the word "mechanical" insert electrical or optical; line 62, claim 3, for "above" read below; and that the said Letters Patent should be read with these corrections therein that the same may conform to the record of the case in the Patent Office.

Signed and sealed this 16th day of February, A. D. 1937.

(Seal)

Henry Van Arsdale
Acting Commissioner of Patents.
